United States Patent Office

Des. 192,572
Patented Apr. 10, 1962

192,572

SOCK

Zephyr Monday, Mount Airy, N.C., assignor to U-Stretch
Corporation, Mount Airy, N.C., a corporation of North Carolina

Filed Nov. 16, 1960, Ser. No. 62,929

Term of patent 14 years

(Cl. D47—7)

I claim:

The ornamental design for a sock, as shown and described.
